(57) **CLAIM**

A new, original, ornamental design for a nozzle for automobile painting, as shown.

DESCRIPTION

FIG. 1 is a perspective view of the nozzle for automobile painting where claimed inner body is attached to unclaimed external body;

FIG. 2 is a front view thereof, the back view being a mirror image thereof;

FIG. 3 is a left side view thereof, the right side view being a mirror image thereof;

FIG. 4 is a top view thereof;

FIG. 5 is a bottom view thereof;

FIG. 6 is a cross section view through section 6-6' of FIG. 4;

FIG. 7 is a perspective view where claimed inner body is detached from unclaimed external body;

FIG. 8 is an enlarged top view of claimed inner body thereof;

FIG. 9 is an enlarged bottom view of claimed inner body thereof; and,

FIG. 10 is an enlarged left side view of claimed inner body thereof.

The broken lines in the drawings show external body of the nozzle for automobile painting and form no part of the claimed design.

1 Claim, 8 Drawing Sheets
